Harry R. Reynolds and Ignatius Montana,
Brooklyn, N. Y.

Application May 7, 1946, Serial No. 129,417

Term of patent 3½ years

(Cl. D34—15)

To all whom it may concern:

Be it known that we, Harry R. Reynolds and Ignatius Montana, both citizens of the United States and both residing in the county of Kings, city of Brooklyn, and State of New York, have invented a new, original, and ornamental Design for a Whirligig Toy, of which the following is a specification, reference being had to the accompanying drawing, forming a part thereof.

Figure 1 is a view in perspective of the whirligig toy showing our new design.

Figure 2 is a rear end view on reduced scale of the toy shown in Figure 1, and

Figure 3 is a top plan view on reduced scale of the toy illustrated in Figure 1.

We claim:

The ornamental design for a whirligig toy, as shown and described.

HARRY R. REYNOLDS.
IGNATIUS MONTANA.
